UNITED STATES PATENT OFFICE

ARLEN R. SOLLENBERGER, OF FAIRBURY, NEBRASKA

FENCE POST

Application filed December 12, 1929. Serial No. 413,587.

The present invention relates to fence posts and more particularly to a fence post which may be conveniently and easily anchored in the ground.

5 An object of this invention is to provide a fence post of this character which is preferably constructed of metal but is so constructed that the conventional type of staples may be used for holding the wire thereupon.

10 Another object of this invention is to provide a fence post of this character having anchoring means positioned adjacent the bottom thereof for securely anchoring the post in the ground.

15 A further object of this invention is to provide a device of this character with a reinforced top portion so that the post may be driven into the ground by the use of a hammer or the like.

20 The above and various other objects and advantages of this invention will in part be described in and in part be understood from the following detailed description of the present preferred embodiment, the same being illustrated in the accompanying drawing wherein:—

Fig. 1 is a detail side elevation of a fence post constructed according to the preferred embodiment of this invention;

30 Fig. 2 is a transverse section partly in elevation of the device taken substantially on the lines 2—2 of Fig. 1, showing a small staple mounted therein;

35 Fig. 3 is a transverse section partly in elevation of the device showing a large staple mounted therein; and

Fig. 4 is a section taken on line 4—4 of Figure 2.

Referring to the drawing wherein like numerals of reference designate corresponding parts throughout the several views, the numeral 10 designates generally a fence post of substantially tubular construction which is provided at the lower end thereof with a

45 pointed section 11 for engaging the ground. The body portion 12 of the fence post is substantially annular in cross section and is provided with an elongated slot or split portion 13.

50 One edge portion of the body member 12 is

bent inwardly as at 14. The opposite free end of the body member 12 is bent inwardly as at 15 and substantially parallels the extension 14. The inner end portion of the extension 15 is preferably looped or reverted as 55 at 16. The extensions 14 and 15 are preferably positioned in close proximity to each other so as to firmly engage therebetween a staple or the like which may be driven through the open or slotted portion 13. 60

The upper end of the fence post 10 is provided with a cap or reinforcing member 17, the lower edge portion of which extends downwardly from the upper end of the post 65 so as to prevent opening of the slot 13 and to reinforce the upper end of the post to permit driving of the post into the ground in the conventional manner. The fence post 10 is provided with a plurality of anchor members 18 which are preferably positioned spaced 70

upwardly from the lower end portion thereof and may be secured to the post by means of rivets 19 or the like. The anchor members 18 may be mounted at diametrically opposed sides of the post 10 and, if desired, 75 may be positioned at spaced intervals along the body of the post so as to provide a firm anchor for the post when it is driven into the ground.

In the use of this device, the post 10 may 80 be driven into the ground in the conventional manner so that the anchor members 18 are positioned within the ground so that they will hold the fence post against movement in the ground. The fence wire may be positioned against the body 12 of the fence post and against the slotted portion 13 thereof. The fence post 10, being constructed of substantially resilient metal, permits the driving of a staple or the like into the slotted portion 13 thereby forcing the inner extensions 14 and 15 apart. The looped portion 16 of the extension 15 will effectively turn over the pointed end of the staple and prevent ready removal thereof. 90

As shown in Figure 4, the spring or clamping members 14 and 15 are provided with corrugations so as to prevent the staples from sliding vertically within the slotted portion 13. In addition to acting as a clinch- 95

ing member, the loop portion 16 provides a resilient clamping member which is adapted to prevent the spring members 14 and 15 from being sprung apart so that the staple 5 will be firmly gripped therebetween.

It will, of course, be understood that various changes and modifications may be made in the details of construction and design of the above specifically described embodiment 10 of the invention without departing from the spirit thereof, such changes and modifications being restricted only by the scope of the following claims.

What is claimed is:—

- 15 1. A fence post of the character described comprising a split body member, said body member having a restricted lower end portion, and staple clinching means mounted on said body member and extending inwardly of the 20 split portion thereof, said staple clinching means comprising a pair of substantially parallel extensions, one of said extensions having a looped inner end portion whereby to clinch the pointed end of a staple therebetween.
- 25 2. A fence post of the character described comprising an elongated annular body, said body being split longitudinally, the free ends thereof being bent inwardly in substantially 30 parallel relation to each other, one of said ends being longer than the other and adapted to overlap the other end whereby to resiliently resist separation of the free ends.

In testimony whereof I hereunto affix my
35 signature

ARLEN R. SOLLENBERGER.
